(57) **CLAIM**

The ornamental design for a medicine crusher, as shown and described.

DESCRIPTION

FIG. 1 is a top perspective view of a medicine crusher showing my new design;

FIG. 2 is a front view thereof;

FIG. 3 is a rear view thereof;

FIG. 4 is a left side view thereof;

FIG. 5 is a right side view thereof;

FIG. 6 is a top side view thereof;

FIG. 7 is a bottom view thereof;

FIG. 8 is a right side view thereof with one handle shown in a first alternative position; and,

FIG. 9 is a right side view thereof with one handle shown in a second alternative position.

The broken line illustrations in the drawing figures of the internal portions and bottom portions of the handles are for illustrative purposes only and form no part of the claimed design.
